Primary Examiner — Karen S Acker*Assistant Examiner* — Jasmine Mlinarcik(74) *Attorney, Agent, or Firm* — O'Banion & Ritchey LLP; John P. O'Banion(57) **CLAIM**

The ornamental design for a visor, as shown and described.

DESCRIPTION

FIG. 1 is a front perspective view of a visor showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom view thereof; and,

FIG. 8 is a front perspective view thereof showing the visor in a position of use.

The broken line showing of the face shield and mini-shield depicts the environment of the claimed design and forms no part thereof.

1 Claim, 4 Drawing Sheets(56)
